ABSORPTION REFRIGERATING APPARATUS

Edward Gruber, Cleveland, Ohio, assignor to
Edmund E. Allyne, Shaker Heights, Ohio

Application January 21, 1932, Serial No. 588,036

7 Claims. (Cl. 62—120.5)

The invention disclosed in this application relates to refrigerating apparatus of the absorption type.

Where, in absorption refrigerating apparatus, a still-absorber, condenser and evaporator are connected in operative cycle in the order mentioned, and a drain is connected between the liquor space of the evaporator and the still, there is an undesirable tendency for the useful refrigerant to take the easier course through this drain back to the still rather than back through the condenser, thereby shortening the refrigerating cycle by diminishing the supply of useful refrigerant. To overcome this defect in circuits of this type, a by-pass is provided around the condenser, suitably loaded or trapped toward the evaporator so that the returning gas may find an easier course through the by-pass than through the drain on its way back to the still. In one arrangement the by-pass balance leads from the evaporator to a point in the circuit substantially at or slightly below the normal level of the liquor in the still whereby, during the heating period, this by-pass is sealed against the passage of gas through it to the evaporator and the gas must flow in the regular course through the condenser to the evaporator, while during the refrigerating cycle, the drain tube connection with the balance tube offers the counter action for pressure on top of liquid in the evaporator, holding the evaporator liquid in equilibrium during refrigeration, the gas passes freely from the evaporator directly back to the still without having to pass through and overcome the resistance of the other circuit through the condenser.

In another form of by-pass conduit is connected to the gas space of the evaporator and leads back to the connection between the rectifier and condenser with suitable trap means in the conduit to prevent the direct passage of gas, during the heating period, to the evaporator, but adapted to permit the free passage of the returning gas from the evaporator directly to the rectifier during the refrigerating cycle, thus by-passing the condenser. This of course is much easier than a return through the drain because there is no seal at the evaporator end of this by-pass pipe, as is the case with the drain.

Such an arrangement is not only useful for overcoming one of the difficulties of a drain of the type mentioned, but is also effective in reducing the time factor necessarily involved in cooling the still at the beginning of the refrigerating cycle. In other words, refrigeration is started earlier in apparatus arranged in this way by rea-

son of the fact that less drop in pressure toward the still is necessary to produce appreciable return of gas from the evaporator.

The foregoing and other features of invention will be apparent from the following description, drawing and claims.

Referring to the drawing, Fig. 1 is a diagrammatic view of a circuit including the invention; and Fig. 2 is a detail view of the connections between the drain and by-pass pipes and the gas and liquid return pipe.

In the drawing, 1 represents a still-absorber in communication with a circulatory cooling loop comprising an up leg 2 and a down leg 3, connected to a coil 4 shown in elevation but normally arranged horizontally. This loop coil may be cooled by any suitable means such as the fins indicated at 5. During the heating period there is no circulation through the loop, but it will be set up during evaporation by the returning gas which enters at 6 from the gas and liquid pipe 7. This pipe extends up above the still and to a point near the top of a liquid seal trap 8 closed except for the pipes which enter it. Extending upward from the boiler is the up leg 9 of a hairpin loop entering the bottom of a header 10 communicating at its other end with a down leg 11 entering the trap and extending to a point near the bottom. Connected to the top or gas space of this trap is a rectifier pipe 12 having two branches entering at the points 13 and 14 formed at the lower edge of a skin-type rectifier and comprising an inner tube 15 and outer tube 16. These two tubes telescope with respect to each other and are spaced very closely to form between them a very narrow annular cavity for the gas passing through the rectifier. The lower and upper edges are both sealed except for the pipes which enter said cavity and either or both walls may be provided with a multiplicity of fins 17, the outer one being as shown in the drawing. At the top, a rectifier condenser pipe 18 connects the top of the rectifier with the top of the condenser.

The condenser is similar in structure to the rectifier and includes an inner wall 19 and outer wall 20, very closely spaced as before, to form an annular cavity between them in communication with the pipe 18. These two telescoping pipes are sealed together at their upper and lower edges and the chamber within the inner wall 19 is closed by suitable upper and lower caps 21 and 22 respectively.

Communicating with the annular cavity between the two tubes 19 and 20 is a suitable bot-

tom sump 23 connected to an evaporator pipe 24 leading up to and discharging into a downwardly inclined larger evaporator tube or pipe 25 connected to a dome 26 on the top of the evaporator 27. The evaporator is provided with a sump 28 into which is run the end of a drain pipe 29. The drain pipe extends upwardly through the evaporator 27 and outwardly through tube 25, and communicates with the enlarged upper portion 31 of pipe 30. The lower portion of pipe 30 is reduced in diameter as indicated by numeral 32. The reduced diameter portion 32 of the pipe 30 is joined to the gas return pipe 7 at a point 32' which is at approximately the normal level or 15 slightly below the normal level of the liquid in the still at the beginning of the heating period.

Connected to the evaporator pipe 25 is a by-pass or balancing pipe 33 which communicates with the gas and liquid return pipe 7 at the point 20 indicated at 34, slightly below the point 32' where the drain enters the pipe 7. The still ends of the drain and by-pass pipes must be submerged at all times during the heating period, because the outgoing gas, during the heating period, must 25 never pass through these pipes but must pass up through the trap 8, and through the rectifier into the condenser and there be liquefied. The liquefied ammonia in the condenser, of course, is driven up to the evaporator from time to time.

If desirable, the upper cap 21 and the lower cap 22 may be provided with water pipes 35 and 36 respectively, which may communicate with the top and bottom of a water tank 37 for impounded or running water, to thereby cool the 30 condenser by thermosyphonic circulation.

During the heating period the ammonia gas is 40 driven from the absorbent in the still through the loop to the bottom of trap 8 where it bubbles up through the liquor and passes out from the top thereof to the rectifier and thence to the top of the condenser where it passes down and is condensed and liquefied, ultimately collected in liquefied form in the evaporator. In the meantime, however, no gas or liquor from the boiler is 45 permitted to flow through the pipe 33 to the evaporator because the point 34 is always submerged during the heating period and a water seal is formed which will prevent such passage. When the heating period is over, a drop in temperature 50 at the still lowers the pressure at this point, resulting in refrigeration at the evaporator and return of the expanded gas through the pipe 33 directly to the gas and liquid return pipe, from whence it must flow to the up leg 2 and into the still. The resistance to flow through the pipe 33 is far less than the resistance through the drain or through the condenser, rectifier, etc., hence the gas takes this easier course through the pipe 33. In going the other way it must overcome any 55 column of liquid in the pipe 24 and the resistance of such a column is far greater than that through the pipe 33. This resistance through the by-pass is similarly less than that created by the seal at the evaporator end of the drain.

The enlarged portion 31 of the drain pipe produces a very important function, especially when used with smaller pipes leading to the evaporator and to the gas and liquid return pipe. The point 31', which is the junction of the portion 31 and 60 the portion 32 should be high enough to insure a complete rise in the smaller pipe 32 for the complete drain of the evaporator, and its level must be determined not only by the height of the drain riser in and from the evaporator, but also 65 by the height of the column in the liquid seal

trap 8 which of course determines the resistance to the flow of gas from the still. The enlarged central portion 31 provides for the collection of ample gaseous medium between the upper and lower seals in the drain pipe so that considerable movement of liquor in the still portion may take place without material compression of the gaseous medium and preventing any siphoning of liquor from the evaporator to the still. In this way ample draining of the evaporator is assured. 10

As shown in Fig. 2, the drain pipe portion 32 is provided with an upturned end portion 32' which communicates with the pipe 7 at the point 32''. The balancing or by-pass tube 33 on the other hand has a downwardly inclined portion 15 33' which enters the tube 7 at substantially the point 34. In this way the entering portions of the drain and the by-pass or balancing tube project their streams in opposite directions into the pipe 7 so that one does not influence the other. 20

What I claim is:

1. In absorption refrigerating apparatus, a still-absorber, condenser and evaporator connected in operative cycle in the order mentioned, a pressure drain conduit having a liquid seal connection with the evaporator and communicating with the still-absorber, said drain conduit being enlarged intermediate its ends, and a by-pass gas return connection leading from the gas space of the evaporator and provided with sealing 25 means effective to prevent flow toward the evaporator and arranged to permit free flow of returning gas from the evaporator toward the still around the condenser.

2. In absorption refrigerating apparatus, a 35 still-absorber, condenser and evaporator connected in operative cycle in the order mentioned, a pressure drain conduit enlarged intermediate its ends having a liquid seal connection with the evaporator and communicating with the still- 40 absorber, and a by-pass gas return connection leading from the gas space of the evaporator to the still and communicating therewith at a point below the liquor level during the heating period.

3. In absorption refrigerating apparatus, a still- 45 absorber, condenser and evaporator connected in operative cycle in the order mentioned, a pressure drain pipe having an enlarged diameter intermediate its ends leading from the bottom of the evaporator and connected in the circuit towards the still, and a by-pass gas return connection leading from the gas space of the evaporator to the still and communicating therewith at a point below the still liquor level during the 50 heating period.

4. In absorption refrigerating apparatus, a still-absorber, condenser and evaporator connected in operative cycle in the order mentioned, a liquid seal trap connected in the circuit adjacent the still, a cooling loop for the still, a gas and liquid return conduit leading from a point near the top of the liquid seal trap to the loop, a drain conduit connected to the bottom of the evaporator and communicating with the gas and liquid return conduit, and a by-pass for the gas during 65 the refrigerating cycle, comprising a conduit connected with the gas space of the evaporator and communicating with the gas and liquid return conduit.

5. In absorption refrigerating apparatus, a 70 still-absorber, condenser and evaporator connected in operative cycle in the order mentioned, a liquid seal trap connected in the circuit adjacent the still, a cooling loop for the still, a gas and liquid return conduit leading from the liquid 75

seal trap to the loop, a drain conduit connected to the bottom of the evaporator and leading to the gas and liquid return conduit, and a by-pass for the gas during the refrigerating cycle, comprising a conduit connected with the gas space of the evaporator and communicating with the gas and liquid return pipe.

6. Absorption refrigerating apparatus as in claim 5, wherein the by-pass pipe is connected in

the gas and liquid return pipe below the drain connection.

7. Absorption refrigerating apparatus as in claim 5, wherein the by-pass pipe is connected in the gas and liquid return pipe below the drain pipe, and the drain and by-pass pipes lead into the gas and liquid return pipe in opposite directions.

EDWARD GRUBER.
